UNITED STATES PATENT OFFICE.

WALTER JACKSON, OF LEICESTER, ENGLAND, ASSIGNEE TO UNITED SHOE MACHINERY COMPANY, OF PATERSON, NEW JERSEY, A CORPORATION OF NEW JERSEY.

MACHINE FOR USE IN FINISHING SHOES.

1,102,511.

Specification of Letters Patent.

Patented July 7, 1914.

Application filed June 16, 1908. Serial No. 483,797.

To all whom it may concern:

Be it known that I, WALTER JACKSON, a subject of the King of Great Britain, residing at Leicester, in the county of Leicester, England, have invented certain Improvements in Machines for Use in Finishing Shoes, of which the following description, in connection with the accompanying drawings, is a specification, like reference characters on the drawings indicating like parts in the several figures:—

This invention relates to machines for finishing boots or shoes and has particular reference to machines for top ironing, *i. e.*, applying a narrow band of wax to the marginal portion of the tread face of shoe soles.

In a machine according to this invention the tool or top iron, which is supplied with wax or like material, is so mounted as to be capable of rotation and reciprocation or oscillation, preferably at different speeds, the combination of these motions securing a more efficient distribution and laying of the wax on the work than heretofore.

A further feature of the invention is that the wax instead of being supplied directly to the tool by a revolving wheel, a wick or the like, is first fed from a rotatable wheel to a pad or the like of absorbent material and from thence to the tool, so that only the required quantity of wax is supplied to the tool, and the necessity for providing a device for removing the superfluous wax from the working face of the iron is avoided.

In a preferred construction, the shaft upon which the top-ironing tool is mounted is journaled in a pivoted frame and means are provided for rotating the tool and for oscillating the frame.

The invention will now be described in detail with the aid of the accompanying drawings which illustrate a convenient embodiment of the invention, it being understood however that the following description and drawings are merely by way of example and that various alterations in the arrangement and construction of the parts could be made without departing from the spirit of the invention:—

Figure 1 represents in side elevation, with parts in section, sufficient of a top-ironing machine to enable this application of the invention to be understood; Fig. 2 is a detail on a larger scale; Fig. 3 is a plan in detail of the top-ironing wheel, the wax-

lifting wheel and the parts immediately associated therewith; Fig. 4 is a plan of a part of the machine represented in Fig. 1; and Fig. 5 is a similar plan with certain of the parts in a different position.

The machine frame 1 is provided with a forward extension or arm 2 upon which an oscillating frame 3 is pivoted. The said frame carries the top-ironing wheel 4 which is secured upon a spindle 6 that is mounted 60 in bearings in the said frame and is provided at its upper end with a gear wheel 8. This gear wheel receives motion through an idler gear wheel 10 mounted on a stud 12 secured to the oscillating frame from another gear wheel 14 secured upon the upper end of a vertical spindle 16. The oscillating frame 3 swings upon a sleeve 20, which surrounds the shaft 16 and is clamped in the forward extension or arm 2 of the machine frame as at 21, said frame having 70 bearings for the sleeve above and below the arm 2.

At the upper end of the vertical shaft 16 is a worm wheel 22 which gears with a worm 24 formed upon an extension 25 of the main shaft 26 which latter is mounted in bearings upon the machine frame and driven from the counter shaft on the machine through the instrumentality of a belt 28 passing around pulleys 30 and 32 situated respectively on the main and counter shafts. For a purpose hereinafter to be set forth the forward journal or extension 25 of the main shaft 26 is formed somewhat 80 aslant with its axis inclined to and crossing the axis about which the said shaft turns at a point adjacent to the worm wheel 22 so that the oscillatory movement of the worm 24 with respect to the worm wheel 22 is so slight as not to appreciably effect the relation of the worm and gear. The lower end of the vertical shaft 16 is provided with a worm 34 which meshes with a worm wheel 35 loosely mounted upon a horizontal shaft 36 which also carries the wax-supplying wheel 38. The shaft 36 is mounted above a wax trough 40; hereinafter to be more fully described, in such a manner that the wax-supplying wheel is partly immersed in 105 the wax. The worm wheel 35 is held in frictional engagement with the hub 42 of the wax-supplying wheel 38 by a sleeve 44 which bears against the said worm wheel through the action of a spring washer 45 110

seated between the end of the sleeve and a nut 46 screwed upon the end of the horizontal shaft 36. By unslackening the nut 46 the pressure of the worm wheel 35 upon the 5 hub of the wax-supplying wheel 38 will be removed whereby the said worm wheel will be rotated idly without revolving the wax-supplying wheel. This arrangement of friction drive also, it will be evident, constitutes a safety device to prevent breaking 10 should the machine be started before the wax is melted. The horizontal shaft 36 is carried in bearings forming part of a frame 48 bolted to the wax trough 40.

15 Wax is conveyed by the rotation of the wax-supplying wheel 38 to a pad, or wiper 50 preferably of felt which is mounted upon a spring arm 52 secured to the oscillating frame 3, the pad or wiper also engaging the 20 top-ironing wheel 4 so that the wax received from the wheel 38 is spread thereon evenly and the supply of wax maintained constant. The disposition of the wax-supplying wheel in relation to the top-ironing wheel is such 25 that although one side of the periphery of the wax-supplying wheel comes into close proximity to the top-ironing wheel and touches the pad or wiper the opposite side of the said periphery is remote from the 30 top-ironing wheel thus leaving ample free space for the manipulation of the work. This arrangement also allows the wax trough to be of large capacity.

The wax trough 40 is provided with a 35 water jacket 54 which is heated by a "Bunsen" burner 55 the flame of which is received in a hood-like chamber 56 which extends downwardly from the jacket 54. Pipes 58, 59 connect the water jacket with 40 an auxiliary tank or bath 60 arranged preferably at a higher level and the whole water jacket system can conveniently be connected removably to the machine frame, for example, as shown in the drawings by bolts 45 61 which pass through lugs on the auxiliary tank and screw into the machine frame. The top-ironing wheel 4 is also provided with a heating device which for convenience can be formed of a burner 62 secured to the 50 machine frame.

To swing the oscillating frame upon the sleeve 20 the aslant extension or journal 25 hereinbefore referred to is employed. This extension is encircled by a sleeve 65 within 55 which it turns, the sleeve being provided with pivots or trunnions 66 (see Figs. 4 and 5) which are received in bearings 68 formed in the oscillating frame or an extension thereof. Continuous rotation of the 60 main shaft 26 producing a gyration of the aslant extension 25 will cause the sleeve 65 to oscillate whereby the movement of the pivots or trunnions 66 endwise in a horizontal plane will correspondingly effect the 65 movement of the oscillating frame 3. The

sleeve 65 is formed with a recess to receive the worm wheel 22 hereinbefore referred to and with a bearing by which it slides vertically on the sleeve 20.

The extension of the oscillating frame 3, hereinbefore referred to as being provided with bearings 68 for the pivots 66 of the oscillating sleeve 65, is formed as a closed gear box which can contain lubricant, a pulley 70 being provided on the shaft 26 which pulley carries a chain or the like 72 75 to raise the lubricant from the box and so maintain the aslant extension 25 and worm gear 22, 24 properly lubricated. The gear box is made in two portions secured together by bolts and the rear bearing in which the shaft 26 turns is constructed so as to permit the shaft and its sleeve to be raised whereby access to the gear wheels 8, 10 and 14 is facilitated.

80 A scraper 75 is shown in the drawings as secured to the oscillating frame 3 in a position between the pad 50 and the point where the work is presented, the function of which scraper is to remove from the top-ironing wheel all the wax except that 85 on the portion of the top-ironing wheel which is required to distribute the wax on the work, in this case the under side of the flange and that marginal edge of the tool 90 which engages the edge face of the sole. The pad 50 will preferably be shaped to supply these faces of the tool with wax and to avoid as much as practical the application 95 of wax to other portions of the tool. By 100 the provision of the pad 50 there will be little tendency for the working face of the wheel to receive more wax than is necessary for use.

105 In the operation of the machine the rotation of the main shaft 26 effects the continuous rotation of the top-ironing wheel 4 through the worm gearing 22, 24 and gear wheels 8, 10, 14 and at the same time oscillates the said wheel by the vibration of the 110 sleeve 65 actuated by the aslant extension 25 which movement is transmitted to the oscillating frame 3 by reason of the pivots 66 upon the sleeve acting upon the extension of the said frame. The oscillating or reciprocating movement of the tool is preferably, 115 and as herein shown, much faster than its rotation. At the same time the wax-supplying wheel 38 is rotated through the revolution of the shaft 16 driven by the worm gear 22, 24, aforesaid, the motion from the shaft being transmitted through the worm gear 34, 35 to the said wheel 38 and thereby lifting the wax from the trough 40 to convey 120 it to the top-ironing wheel by means of the spring-mounted pad 50 which is carried by the oscillating frame 3 and engages both the wheel 38 and top-ironing wheel 4. The pad may have continuous engagement with the wheel 38 or it may make and break contact 125 130

- with the oscillation of the frame 3 which constantly moves it toward and from said wheel.
- The top-ironing wheel is preferably formed with the acting face 80 on its end which is adapted to apply to the tread face of the sole a band or stripe of wax which may advantageously be of a color to contrast with the appearance of the main portion of the shoe bottom and will extend from the edge of the sole inwardly far enough to cover and fill with wax the break in the surface of the sole where the channel was cut. The oscillating movement of the tool in addition to its rotary movement facilitates the filling of this break in the surface of the sole. The tool also preferably has the edge face 82 which engages the face edge of the sole and between the faces 80 and 82 the tool is formed, as by the annular groove 84 to shape or reshape the annular edge or corner of the sole and, it may be, produce thereon the bead or ornamental projection indicated at 85 in Fig. 2.
- Having explained the nature of this invention, indicated some of the advantages and certain purposes for which it may be used, and described a preferred construction embodying the invention, I claim as new and desire to secure by Letters Patent of the United States:—
1. In a shoe finishing machine, the combination with a rotary finishing tool, of means for rapidly reciprocating the tool over the work in substantially the plane of its rotation and means for imparting a relatively slow turning movement to the tool.
  2. A wax finishing machine, having in combination a wax applying member, and wax supplying means comprising a wax reservoir, a wax lifting wheel and a pad relatively stationary with respect to the applying member arranged to receive the wax from the wheel and deliver it to the applying member.
  3. A wax finishing machine, having in combination a wax applying tool, a wax reservoir, a wheel running in the reservoir and out of touch with the tool, a member composed of absorbent material arranged to contact with the wheel and the tool and relatively stationary with respect to the tool, and means whereby the wheel and the tool are heated to maintain in softened condition the wax on the said member of absorbent material.
  4. A wax finishing machine, having in combination a wax applying member, and wax supplying means comprising a wax reservoir, a transferring wheel, a pad to deliver the wax to the applying member and means for moving the pad from and toward the wheel.
  5. A top-ironing machine, having in combination a rotary tool to engage the tread face of a sole, a wax reservoir, a wax lifting wheel and a felt pad relatively stationary with respect to the tool and arranged to engage the wheel and the work rubbing face of the tool.
  6. A machine of the class described, having in combination a rotary top-ironing tool, a relatively stationary wax supplying pad arranged to engage the work rubbing face of the tool, a wax lifting device arranged to supply wax to said pad and a scraper formed and arranged to remove any wax that may get upon the outer peripheral edge of the tool.
  7. A machine of the class described, having in combination a rotary top-ironing tool, a relatively stationary device for applying wax to the lower work rubbing face of the tool, means for conveying wax to said device and a scraper between the said device and the work to clean the periphery of the tool.
  8. A machine of the class described, having in combination a rotary top-ironing tool turning in a substantially horizontal plane, a wax feeding disk turning in a substantially vertical plane, and a device arranged to engage a vertical side face of the disk and the horizontal work rubbing face of the tool to conduct the wax from the wheel to the tool.
  9. In a machine for finishing shoes, a rotatable finishing tool, means for driving it and means for reciprocating the tool comprising an oscillatory tool carrying arm, and a gyratory shaft connected with the arm and the driving means.
  10. In a machine for finishing shoes, a rotatable finishing tool, actuating means therefor comprising a rotatable shaft, a screw and gear connection between the tool and the shaft for rotating the tool, and a crank connection between the tool and shaft for reciprocating the tool.
  11. A machine for finishing shoes, having in combination a wax lifting device, a wax applying device, means for reciprocating the latter device with relation to the former, and a wax transerrer of yielding material located between the two devices.
  12. A machine for finishing shoes, having in combination a wax lifting device, a wax applying device, means for reciprocating the latter device with relation to the former, and a wax transerrer yieldingly supported and arranged for engagement with the reciprocating wax applying device and with the lifting device.
  13. A machine for finishing shoes, comprising, in combination, a rotatable finishing tool, a frame supporting said tool, a driving shaft having an aslant portion, connections between said frame and said aslant portion whereby the rotation of the shaft imparts a

rapid oscillatory movement to said frame, connections between said shaft and tool for rotating the tool, a wax reservoir and driven conveying means operated from said shaft

5 to supply wax to said tool.

14. A machine for finishing shoes, comprising, in combination, a rotary tool, an oscillating frame supporting said tool, a driving shaft having an aslant portion, connections between said frame and said aslant portion to cause the shaft to oscillate the frame, a worm on said aslant portion of the

shaft, means operated by said worm to rotate said tool and driven wax conveying means operated by said worm to deliver wax 15 to said tool.

In testimony whereof I have signed my name to this specification in the presence of two subscribing witnesses.

WALTER JACKSON.
